UNITED STATES PATENT OFFICE

JOSEPH A. SANDFORD, JR., OF EAST LIVERPOOL, OHIO, ASSIGNEE TO WIRE D. THOMAS AND SONS COMPANY, OF EAST LIVERPOOL, OHIO, A CORPORATION OF OHIO.

POST-INSULATOR

1,109,470.

Specification of Letters Patent. Patented Sept. 1, 1914.

Application filed February 21, 1892. Serial No. 749,898.

To all whom it may concern:

Be it known that I, JOSEPH A. SANDFORD, Jr., a citizen of the United States of America, and residing in the city of East Liverpool, in the county of Columbiana and State of Ohio, have invented a certain new and useful Improvement in Post-Insulators, of which the following is a specification.

My present invention relates to post insulators and particularly to the means by which the various insulator units are rigidly spaced apart, the object of my invention being to provide an improved spacing device which will make it possible to manufacture and ship the insulator units independently of one another, so that they may be readily assembled at the place of use, and also in case of breakage, to readily replace an injured or imperfect unit by a new unit without necessitating the abandonment of the insulator as a whole.

In the accompanying drawing, Figure 1 is a side elevation of a post insulator embodying my invention and in which portions are broken away the better to illustrate my invention; Fig. 2 is a side elevation half in section of an insulator unit in which my invention is embodied and drawn to a larger scale; Figs. 3 and 4 are similar views of the upper and lower portions respectively of the spacing casting; Figs. 5 and 6 are similar views of a modified construction; Figs. 7 and 8 are similar views of the top and base castings.

The insulator to which the present invention relates is of that type which in assembled condition comprises a series of insulator units, such as A, rigidly spaced apart and united by a series of metal spacing members. Each of these spacing members as here shown comprises a cap element 10 fitted over the head 11 of an insulator unit A to which it is united by cement 12, engaging the ribs and grooves 13 and 14 formed upon said parts to secure a better mechanical joint with the cement. Each spacing member comprises also an independent pin element 15 cemented at 20 within the head of the superposed insulator. Any suitable co-operating means may be formed upon the adjacent ends of the pin and cap elements by means of which they may be rigidly secured together. I have shown, for the sake of illustration, the simplest form of union, viz., by means of cooperating male and female

thread. Thus the lower end of the pin element is slightly enlarged and an internal shoulder 21 formed therein below which the interior of the pin is threaded. Similarly the upper end of the cap is inwardly offset at 23 to form a shoulder above which extends a neck 24 which is threaded to cooperate with the threads 22 at the lower end of the pin. Each insulator unit A will thus carry cemented in position a cap 10 and a pin 15, the one surrounding and the other within the head 11 of the insulator, as illustrated in Fig. 2. In this condition the units may be shipped to their destination where the user may assemble as many units as may be desired depending upon the service demanded. On an insulator already established may have its capacity increased by the insertion of additional insulator units. Again, in case of injury to an insulator unit A it is now possible to replace the defective unit alone, without discarding the entire insulator as has heretofore been necessitated by the customary construction of insulators of this type.

For each pile of insulator units which forms the post insulator, a flanged bottom casting 16 is provided, which for the sake of symmetry in the assembled insulator, conforms substantially to the shape of one of the cap elements 10, except that it is provided at its lower edge with an outwardly extending peripheral flange 17 perforated to permit the passage therethrough of securing screws. A threaded nipple 18 is formed thereon to enter the lower end of the pin 15 carried by the bottom insulator unit of the pile forming the insulator as a whole. Similarly a top casting 19 is provided which comprises an internally threaded nipple 18 adapted to be screwed upon the neck 24 of the cap casting carried by the top insulator unit of the pile. The flange 19 of the top casting is perforated to accommodate securing screws or bolts by means of which a switch or other fitting may be supported thereon.

The spacing elements shown in Figs. 5 and 6 differ from those shown in Figs. 3 and 4, only in that the arrangement of the threads is different. Here the pin element 25 is externally threaded at its lower end 23 instead of internally, as above described, while the cap element is internally threaded at 27 instead of externally. Corresponding

modifications of the bottom and top castings to coöperate with this arrangement of the threads would necessarily have to be made.

Various other modifications of the joint 5 between the parts will readily suggest themselves.

I claim as my invention:—

1. An insulator comprising a series of bell-head, peticated insulator units spaced 10 apart, each unit comprising, as spacing means, a metallic cap permanently secured upon the head of the insulator unit and provided with an axial threaded boss, and a metallic pin permanently secured axially 15 within the head of said unit and having its outer free end threaded, substantially as described.

2. An insulator unit for a built-up insulator, said unit comprising a bell-head insulator, 20 a metallic cap permanently secured upon the insulator head and provided at its outer end with a threaded boss, and a metallic pin permanently secured within the head of the insulator and having its outer end

threaded, said threaded boss on the cap and 25 threaded end of the pin being adapted to respectively engage coöperating members for spacing apart adjacent insulator units in a built-up insulator.

3. For a built-up insulator having a series 30 of insulator units spaced apart, spacing means between adjacent units comprising a metallic cap member permanently secured upon the head of one insulator unit and a metallic pin permanently secured within the 35 head of the superposed insulator unit, the adjacent ends of said metallic cap and pin members being threaded to afford a screw joint between the same, substantially as described.

In testimony whereof I have signed my name to this specification, in the presence of two subscribing witnesses.

JOSEPH A. SANDFORD, Jr.
